US0D1031019S

(12) **United States Design Patent** (10) Patent No.: **US D1,031,019 S**
(45) Date of Patent: ** Jun. 11, 2024

(54) **FACE MASK FRAME**(71) Applicant: **Fisher & Paykel Healthcare Limited**,
Auckland (NZ)(72) Inventors: **Craig Robert Prentice**, Auckland (NZ);
Bernard Tsz Lun Ip, Auckland (NZ);
Mark Arvind McLaren, Auckland (NZ);
Kyle Gregory Brown, Auckland (NZ);
Chris Onin Limpin Hipolito,
Auckland (NZ); **Mark Richard Tomlinson**,
Auckland (NZ); **Melissa Catherine Bornholdt**,
Auckland (NZ)(73) Assignee: **FISHER & PAYKEL HEALTHCARE LIMITED**,
Auckland (NZ)(**) Term: **15 Years**(21) Appl. No.: **29/864,765**(22) Filed: **Jun. 17, 2022****Related U.S. Application Data**

(63) Continuation of application No. 29/654,233, filed on Jun. 21, 2018, now Pat. No. Des. 958,969, which is a continuation of application No. 29/595,877, filed on Mar. 2, 2017, now Pat. No. Des. 824,021, which is a continuation of application No. 29/540,693, filed on Sep. 25, 2015, now Pat. No. Des. 784,516.

(57) CLAIM

The ornamental design for a face mask frame, as shown and described.

DESCRIPTION

FIG. 1 is a top, front and side perspective view of a first embodiment of a face mask frame showing our new design; FIG. 2 is a top, rear and side perspective view thereof; FIG. 3 is a front view thereof;

FIG. 4 is a rear view thereof;

FIG. 5 is a first side view thereof;

FIG. 6 is a second side view thereof;

FIG. 7 is a top view thereof; and,

FIG. 8 is a bottom view thereof.

The broken lines in the drawings depict portions of the face mask frame that form no part of the claimed design.
